UNITED STATES PATENT OFFICE.

WILLIAM PERSON, OF ROCKFORD, ILLINOIS, ASSIGNOR TO EAST ROCKFORD MANTEL COMPANY, OF ROCKFORD, ILLINOIS, A CORPORATION OF ILLINOIS.

SEWING-MACHINE CABINET.

SPECIFICATION forming part of Letters Patent No. 769,018, dated August 30, 1904.

Application filed February 9, 1904. Serial No. 192,857. (No model.)

To all whom it may concern:

Be it known that I, WILLIAM PERSON, a citizen of the United States, residing at Rockford, in the county of Winnebago and State of Illinois, have invented certain new and useful Improvements in Sewing-Machine Cabinets, of which the following is a specification.

The object of this invention is to construct a sewing-machine cabinet in which the platform supporting the machine-head is raised by the opening movement of the cover and held elevated by the cover.

In the accompanying drawings, Figure 1 is a top view of the sewing-machine cabinet in which the cover is open. Fig. 2 is a lengthwise vertical section. Fig. 3 is a transverse vertical section on dotted line *a*, Fig. 2, in which the platform is elevated. Fig. 4 is a transverse vertical section on dotted line *a*, Fig. 2, in which the platform is lowered. Fig. 5 is a section on dotted line *b*, Fig. 2. Fig. 6 is a section on dotted line *c*, Fig. 2.

The cabinet-top 1 is supported by the sides 2 and back 3. The frame 4 is secured to the top and has an opening to the rear side of which is hinged a platform 5 in a manner that it may drop. To the platform is hinged a platform extension 6. A roller 7 is pivotally connected to the rear wall of the cabinet near the end at which the cover is hinged. To the back of the cabinet are secured two brackets 8 near the ends of the cabinet. A bracket 9 is secured to the back of the cabinet between the brackets 8. The brackets, as shown at Fig. 5, are open on their outer face, and the bracket 9 (shown at Fig. 6) has a central opening 10. A rod 11, with outwardly-turned arms 12, is located in the three brackets and held from displacement by the center bracket 9. To the free end of each of the arms 12 is pivoted a link 13, and the other ends of these links are pivotally connected to the under face of the platform 5 near its ends.

To the rod 11 is secured a segmental gear 14. From the bracket 9 extends a stud 15, which supports a toothed quadrant 16, which meshes with the segmental gear 14. From the toothed quadrant extends an arm 17, to

the free end of which is connected a band 18, passing over the roller 7 and connected to the cover 19 at the point 20. The connection of the band 18 with the arm 17 is made adjustable by the threaded rod 21 and nuts 22, placed on either side of the arm, by means of which the proper length may be given to the connection. From the toothed quadrant 16 extends an arm 23, to the free end of which is connected a coiled spring 24, having its outer end connected to a stationary portion of the cabinet.

In use the sewing-machine head is secured to the upper face of the platform, and when the parts are in the position shown at Fig. 4 the platform is dropped into the cabinet and the cover closed over the top. Upon opening the cover the toothed quadrant will be rocked on its pivotal support, which will partially revolve the segmental gear, which in turn will rock the rod and cause the arms to raise and straighten the link connection with the platform until the platform is raised into the position shown at Fig. 3, which will bring the platform flush with the upper surface of the frame. When the cover is being closed, the weight of the sewing-machine head supported upon the platform will, through the links and arms, rock the rod and partially rotate the segmental gear, and its return will move the toothed quadrant, which will increase the tension of the coiled spring and prevent the too sudden descent of the machine-head. The coiled spring will assist in raising the platform and sewing-machine head supported thereby. The brackets 8 serve to hold the ends of the rod in line with the center bearing and also prevent endwise movement of the rod.

I claim as my invention—

1. In a sewing-machine cabinet, the combination of a top, a platform having a hinged connection therewith, a hinged cover, a rod supported in bearings beneath the platform, two arms extending from the rod, links forming a connection between the arms and the platform, a toothed wheel supported by the rod, a toothed quadrant having a pivotal support, and an engagement with the toothed wheel, an arm ex-

tending from the quadrant, and a connection between the arm and cover.

2. In a sewing-machine cabinet, the combination of a top, a platform having a hinged connection therewith, a hinged cover, a rod supported in bearings beneath the platform, two arms extending from the rod, links forming a connection between the arms and the platform,

a toothed wheel supported by the rod, a toothed quadrant having a pivotal support and an engagement with the toothed wheel, and a connection between the quadrant and cover. 10

WILLIAM PERSON.
